UNITED STATES PATENT OFFICE.

ERNEST J. LEES, OF CLEVELAND, OHIO, ASSIGNOR TO THE LEES-BRADNER COMPANY,
OF CLEVELAND, OHIO, A CORPORATION OF OHIO.

GEAR-GENERATOR.

1,108,379.

Specification of Letters Patent. Patented Aug. 25, 1914.

Application filed August 27, 1913. Serial No. 786,931.

To all whom it may concern:

Be it known that I, ERNEST J. LEES, a citizen of the United States, resident of Cleveland, county of Cuyahoga, and State of Ohio, have invented a new and useful Improvement in Gear-Generators, of which the following is a specification, the principle of the invention being herein explained and the best mode in which I have contemplated applying that principle, so as to distinguish it from other inventions.

My invention relates to gear generators and particularly to that feature of the latter which relates to mechanism for changing the speed of rotation of the work-rotating spindle.

The said invention relates to a specific feature shown and described in Patent No. 1,071,163 issued to me Aug. 26, 1913 and consists of means hereinafter fully described and particularly set forth in the claims.

The annexed drawings and the following description set forth in detail certain means embodying my invention, the disclosed means, however, constituting but one of various mechanical forms in which the principle of the invention may be applied.

In said annexed drawings:—Figure 1 is a horizontal section of a gear generating machine embodying my invention. Fig. 2 is a vertical section taken upon the plane indicated by line II—II in Fig. 1. Fig. 3 is a bottom plan of a detail portion of the mechanism shown in Fig. 2. Fig. 4 is a vertical fragmentary section taken upon the plane indicated by line IV—IV in Fig. 1.

As fully described in my above mentioned original application, the illustrated gear generator includes a work-holding and rotating spindle C', to the inner end of which the work is suitably secured. Suitably mounted is the main work-rotating driving-shaft C⁶ to which is fixedly secured a helical gear c²¹, Figs. 2 and 3, this gear engaging with a second helical gear c²² fixedly secured to the lower end of a vertical spindle C⁷. This latter spindle is mounted in suitable bearings formed in a housing C⁸, which itself forms a part of the frame of the work-holding slide, but is made separate therefrom and movably adjustable in a direction transverse with respect to the direction of slide-feed movement, as shown in Fig. 2. The said housing is provided with slots c²³

c²³, through which pass cap-screws c²⁹, by means of which the housing may be fixed to the main frame of the slide C, as will be readily understood.

Intermediately of the ends of the spindle 60 C⁷ is formed or secured a worm C⁹, which engages a worm-wheel C¹⁰ fixed to the work-rotating spindle C', as shown in Figs. 1 and 2. This worm-wheel forms one element of a compound gear, the other element of 65 which consists of a spur-gear C¹¹, Figs. 3 and 4. Slidably mounted upon the shaft C⁶, Fig. 4, is an auxiliary pinion c²⁴, which, when the worm is engaging the worm-wheel, is held in a fixed position by means 70 of a pin c²⁵ passing through an adjacent portion of the slide-frame and into an aperture formed in the pinion, as shown. The relationship of the spur-gear member C¹¹ with the pinion c²⁴ is such that the latter, by 75 removing the pin c²⁵, may be slid into engagement with the former. It will therefore be seen that the work-holding spindle may be driven by the shaft C⁶ either 80 through the medium of the worm-wheel and worm, or through the medium of the spur-gear and pinion. In the latter case, the housing C⁸ is slid over so as to disengage the worm from the worm-wheel, as will be readily understood. In order, however, to 85 prevent any unpremeditated attempt, through carelessness, to drive the pinion simultaneously through the medium of both sets of driving mechanisms, which would result in a breakage of parts, the housing is 90 provided with a lug c²⁶, Fig. 3, which, when the worm is in engagement with the worm-wheel, projects into the path of sliding movement of the pinion c²⁴, thereby preventing the latter from being placed into 95 engagement with the spur-gear C¹¹ until such time as the worm is disengaged from the worm-wheel by sliding the housing in the manner previously described.

When it is desired to drive the work-holding and rotating spindle by means of the pinion and spur-gear, and the former is slid into engagement with the latter, the said pinion is rigidly secured to the shaft C⁶ by means of the pin c²⁵ previously removed. 100 This pin, after the pinion has been given its correct meshing position, is passed through a transverse bore c²⁷ formed in the pinion's body, which registers, under these 105 conditions, with a transverse hole c²⁸, 110

formed in the shaft C^8 , as shown in dotted lines in Fig. 4. It will therefore be seen that by means of the above-described arrangement of parts, the work-rotating 5 spindle may be driven at a given rate of speed by the worm C^9 and worm-wheel C^{10} , or at an increased rate of speed through the medium of the gear C^{11} and pinion c^{24} . As fully described in my above mentioned 10 original application, the main work-rotating driving shaft C^6 is driven by the pulley G through intermediate shafts and gearing, this pulley also driving, through suitable mechanism, the cutter spindle B^{11} 15 mounted upon the adjustable head B' , Fig. 1.

Having fully described my invention, what I claim and desire to secure by Letters Patent is:—

1. In a gear-generating machine, the combination of a main work-holding slide-member; a rotatable work-holding spindle mounted in said slide member; a compound gear comprising a worm-wheel element and a spur-gear element; a worm adapted to 20 engage said worm-wheel and mounted so as to be movable in a direction transverse with respect to its axis; a spindle connected with said worm adapted to drive same; and a pinion movably mounted upon said spindle 25 so as to be capable of being brought into or out of mesh with said spur-gear element; and means for rotatably connecting said pinion with or disconnecting same from said spindle.
- 30 2. In a gear-generating machine, the com-

binaton of a main work-holding slide-member; a work-rotating spindle rotatably mounted in said slide member; a compound gear comprising a worm-wheel element and a spur-gear element; a housing slidably mounted upon said main work-holding slide-member, and having a direction of movement transverse with respect to the direction of sliding movement of said slide-member; a spindle mounted in said housing; a worm fixedly secured to said spindle and adapted to engage the worm-wheel element of said compound gear; a driving-spindle mounted in said main slide-member, and having its axis parallel with the axis of said work-rotating spindle; a screw-gear mounted upon said driving-spindle; a screw-gear mounted upon said worm-spindle and meshing with first-named screw-gear; a lug fixedly secured to or integral 55 with said housing; a pinion slidably mounted upon said driving spindle and adapted to engage said spur-gear element of said compound gear; and means for rotatably connecting said pinion with said 60 spindle and disconnecting same therefrom: said projection lying in the path of sliding movement of said pinion when said worm is in engagement with said worm-wheel.

Signed by me, this 1st day of August, 1913.

ERNEST J. LEES.
